COVER FOR COOKING RANGES

Louis J. Smallen, Los Angeles, Calif.

Application December 21, 1940, Serial No. 371,091

8 Claims. (Cl. 126—214)

This invention relates to cooking ranges and relates more particularly to top structures or covers for console type cooking ranges. A general object of this invention is to provide a simple, attractive and inexpensive cooking range cover of the split folding type.

Another object of this invention is to provide an improved cover for the cooking top of a range which is easily and quickly operated between the closed position where it fully covers the range top and an open folded position where it lies against or adjacent the face of the guard rail without interfering with the condiment containers, lamps, clocks, or other devices on the guard rail.

Another object of the invention is to provide a range cover of the character referred to embodying attractive finishing molds at the under side of its hingedly connected sections which close or occupy the corner and edge spaces, strengthen the cover sections and give the cover the appearance of greater thickness.

Another object of this invention is to provide a range cover of the character mentioned in which the cornice or mold parts are secured in place without using additional screws, bolts, rivets or welding. The finishing elements or mold parts embodied in the cover of the invention are effectively and dependably secured in place by means of interfitting portions and the essential hinge screws and bumper screws, thereby making it unnecessary to use attaching means which might injure the finish and detract from the appearance of the cover structure.

A further object of this invention is to provide a range cover of the character referred to in which the mold or finishing parts are easily and quickly applied and are inexpensive, adding but little to the total cost of the cover structure.

The various objects and features of my invention will be fully understood from the following detailed description of a typical form of the invention, throughout which description reference is made to the accompanying drawings, in which:

Fig. 1 is a fragmentary side view of a cooking range embodying the improved cover of the invention with broken lines illustrating the open position of the cover. Fig. 2 is an enlarged fragmentary front view showing the two cover sections raised before folding down the upper section. Fig. 3 is an enlarged fragmentary vertical detailed sectional view through one of the hinges which connect the sections showing the sections in the same condition as in Fig. 2. Fig. 4 is an enlarged fragmentary front view of the parts in the position shown in Fig. 2 and with certain parts

broken away to appear in vertical cross section. Fig. 5 is an enlarged detailed sectional view through one of the corner blocks and adjacent parts, and Fig. 6 is a similar sectional view through a corner block and a hinge for attaching the cover to the range.

The cover construction of the present invention is adapted to be employed on cooking ranges and similar devices varying considerably in type and design. Further, the invention is capable of substantial modification to adapt it for use in various situations. In the following detailed disclosure I will describe the typical form and application of the invention illustrated in the drawings, it being understood that the invention is not to be construed as limited or restricted to the specific form or application herein described.

The portion of the cooking range illustrated in the drawings includes the range body 10 having a cooking top 11 provided with the usual burners, etc. not shown. The various burners of the range are controlled by handles or control parts 12 at the front of the range body 10. An upwardly extending guard rail 13 is provided along the rear edge of the range top 11 and carries the usual clock 14, condiment containers 15, etc. The range body 10 or its guard rail 13 has a vertical face 16 at the rear edge of the cooking top 11, set or stepped outwardly a short distance from the front face of the rail 13. In accordance with the usual practice the cooking top 11 is flat and horizontal along its marginal portions to receive the cover.

The cover of the present invention may be said to comprise, generally, an inner cover section 17 hinged to the range body 10, an outer cover section 18 hinged to the inner section 17 and marginal mold means 19 on the under sides of the sections 17 and 18.

The cover sections 17 and 18 are elongate rectangular members and as illustrated may be alike or identical. The sections 17 and 18 are formed of sheet metal and their surfaces are suitably finished. In most cases the upper and lower surfaces of the cover sections 17 and 18 are covered with vitreous enamel. The sections 17 and 18 may be plain sheet-like elements provided at their several edges or margins with down turned rims 20. The rims 20 are preferably continuous and uniform and are disposed at right angles to the upper and lower surfaces of the sections 17 and 18. Lateral or inturned flanges 21 extend along the lower edges of the rims 20. The flanges 21 are flat and substantially horizontal to be generally parallel with the bodies of the sections 17

and 18 and are adapted to oppose and lie substantially flush with the surface of the cooking top 11 when the cover is closed. The rims 20 and the flanges 21 may be finished in the same manner as the other parts of the sections 17 and 18. The corners where the rims 20 join the bodies of the sections 17 and 18 and the corners where the flanges 21 join the rims 20 are suitably rounded.

The rear edge of the inner section 17 is pivotally or hingedly connected with the range body 10 so that the section may be swung between the horizontal closed position and the substantially vertical open position. Suitable hinges 22 secure the inner section 17 to the range body 10. In the construction illustrated there are two hinges 22, one hinge being arranged adjacent each end of the section 17. Each hinge 22 has a cheek 23 secured to the range face 16 by screws or bolts 24 and has a similar cheek 25 secured to the inner or rear rim 20 of the section 17. Screws 26, passed through openings in said rim 20 and threaded into elements of the means 19, serve to secure the hinge cheeks 23 to the rim 20. The hinge cheeks 23 and 25 are notched to receive torsional springs 27. The springs 27 surround the hinge pins 28 and have their opposite end portions reacting against the cheeks 23 and 25. The springs 27 exert an upward force or lifting force on the cover section 17 and tend to swing the cover to its open or raised position. However, the springs 27 are of insufficient strength to raise the cover sections 17 from their closed positions and merely assist in raising the cover section when the cover is manually opened. The springs 27 serve to yieldingly or releasably hold the cover section 17 in its raised vertical position. The hinges 22 just described may serve to limit or stop the opening movement of the section 17.

The outer or front cover section 18 is hinged to the forward edge of the inner section 17 so that it may be raised with the section 17 and then swung downwardly and rearwardly to lie against and conceal the under side of the raised section 17. Spaced hinges 29 serve to hingedly or swingably connect the rear edge of the section 18 with the forward edge of the section 17. In the construction illustrated there are three spaced hinges 29 spaced and related so that the outer ends of the cover sections 17 and 18. The cheeks of the hinges 29 may lie flat against the under surfaces of the flanges 21 which extend along the forward edge of the section 17 and rear edge of the section 18. Screws 30 passed through openings in these flanges 21 are threaded into openings in plates 31 at the upper sides of the flanges to secure the hinges 29 to the sections 17 and 18. It will be apparent how the hinges 29 secured to the under sides of the sections 17 and 18 allow the section 18 to be swung between its horizontal closed position and its vertical open position when the cover is opened and closed. Suitable bumpers 32 are secured to the under side of the flange 21 which extends along the forward edge of the section 18. The bumpers 32 are preferably positioned adjacent the opposite ends of the section 18 and are secured in place by screws 33. The bumpers 32 are adapted to engage against or cooperate with the range top 11 to limit the downward swinging of the cover and to support the forward portion of the closed cover.

The mold means 19 conceals, closes and occupies the corners in the under sides of the cover sections 17 and 18 which occur by reason of the edge rims 20 and flanges 21. The means 19 at

the inner cover section 17 includes a rear mold member 34, side mold members 35 and a front mold member 36. The mold members, 34, 35 and 36 are preferably formed of the same stock to be identical in transverse cross section and each has a main pitched or sloping portion 37, a base 38, an up-turned flange 39 extending along the base 38 and an inturned flange 40 on the upper edge of the main portion 37, see Figs. 3 and 5. The mold members 34, 35 and 36 may be formed of sheet metal and may be suitably finished. In practice the mold members 34, 35 and 36 may be plated, for example, their outer surfaces may be chromium plated. The finishing members or mold members 34, 35 and 36 are arranged to have their bases 38 bear against the upper sides of the flanges 21, to have their flanges 39 engage against the inner sides of the rims 20 and to have their flanges 40 engage against the under surface of the cover section 17, assuming the cover to be closed. With this arrangement of the mold members 34, 35 and 36 their main portions 37 extend diagonally or are pitched upwardly and inwardly from adjacent the flanges 21 to the under side of the cover section 17. The members 34 and 36 are arranged along the rear and front margins of the section 17 while the members 35 are arranged at the opposite ends of the section.

The rear mold member 34 is proportioned and arranged to have its opposite ends spaced from and adjacent the opposite ends of the elongate section 17. The mold means 19 at the section 17 further includes corner blocks 41 arranged in the rear corners of the section 17. The blocks 41 may be solid members, as illustrated, or may be hollow members of pressed sheet metal or the like. The blocks 41 are shaped to fit in the corners of the section 17 and have pitched or sloping under surfaces which conform to and lie flush with the surfaces of the main portions 37 of the mold members. Tongues 42 and 43 of slightly reduced thickness are provided on the blocks 41 to extend parallel with the rims 20. Shoulders 44 occur where the reduced tongues 42 and 43 join the bodies of the blocks 41. The tongues 42, which are somewhat longer than the tongues 43, are received in the opposite ends of the rear mold members 34 and are notched or recessed to receive the flanges 39 and 40 of the member 34 as shown at 45 in Fig. 5. The engagement of the flanges 39 and 40 with the block tongues 42 serves to hold the member 34 against downward and forward movement with respect to the blocks and the blocks are secured to the section 17 so that they anchor or attach the member 34 to the section.

The screws 26 which attach the hinge cheeks 25 to the section 17 are utilized to secure the blocks 41 to the section. The screws 26 are threaded into openings 46 in the blocks 41 and their tongues 42 and the blocks and tongues may be formed and proportioned to receive all of the screws 26. When the assembly of the member 34 and blocks 41 has been arranged in place on the section 17 the screws 26 are passed through the openings in the hinge cheeks 25 and rim 20 and are threaded into the openings 46 to fix said assembly to the section 17. The blocks 41 provide ample stock for carrying the screws 26, and the screws 26 for attaching the hinges 22 to the section 17 are utilized to secure the mold member 34 and the corner blocks 41 to the section. When the member 34 and blocks 41 are in place the opposite ends of the member cooperate with the shoulders 44 to hold the member against endwise movement. In this connection it will be observed that the exposed surfaces

of the member 34 and the blocks 41 are flush and the exposed surfaces of the blocks may be plated or finished in the same manner as the exposed surfaces of the member 34.

The side or end mold members 35 are engaged over the tongues 43 of the corner blocks 41 and extend forwardly from the blocks 41 to the forward rim 20 of the section 17. The rear ends of the members 35 may be straight to bear against the shoulders 44 of the blocks 41 and the tongues 34 are notched or received in the same manner as the tongues 42 to receive the flanges 39 and 40 of the members 35. The engagement of these flanges 39 and 40 with the block tongues 34 securely anchors or retains the rear portions of the members 34. The engagement of the members 35 with the shoulders 44 prevents rearward shifting of the members and the forward ends of the members may engage or may be immediately adjacent the forward rim 20 of the section 17 so that the mold members 35 are definitely held against endwise displacement. The members 35 may be easily slipped over the tongues 43 and then swung into position to have their bases 38 engage over the flanges 21 and to have their flanges 39 bear against the end rims 20 of the section 17. It will be observed that no attaching members, such as screws or the like, are required to secure the end members 35 at the rear parts of the mold assembly.

After the end mold members 35 have been assembled in place, as described above, the forward mold member 36 is arranged in place to bear between the forward ends of the members 35 to retain the forward parts of the end members 35 in place. Thus the forward end member 36 acts as a spacer or keystone element which retains or assists in retaining the end members 35. The forward mold member 36 is mitered or bevelled at its ends so that its main portion 37 meets the main portions 37 of the end members 35 along pitched diagonal lines 47. The forward member 36 may have the ends of its flange 40 cut off straight so that it does not interfere with the members 35 and the ends of its base 38 and flanges 39 may be cut off straight to properly cooperate with the members 35. The ends of the member 36 are fitted to the end members 35 to eliminate gaps or cracks and to effectively hold the end members in place.

In accordance with the invention the attaching means for the hinges 29 serve to secure the forward mold member 36 in place. The base 38 of the forward mold member 36 has openings 48 for passing the screws 30 and the above mentioned plates 31 are arranged at the upper or inner side of the base 38. The plates 31 may be welded or otherwise fixed to the flange 39 or to the base 38 or both. When the forward mold member 36 has been arranged in place between the side mold members 35 the screws 30 are passed through the openings in the hinges 28, the flanges 21 and the bases 38 and are threaded into the plates 31. This effectively secures the member 36 and completes the attachment of the mold means 19 to the section 17.

The mold means 19 at the forward cover section 13 is similar to the means 19 at the section 17 comprising a front mold member 50, side mold members 51 and a rear mold member 52. The mold members 50, 51 and 52 are of the same shape or cross section as the members 34, 35 and 36 and the same reference numerals are applied to their main portions 37, bases 38 and flanges 39 and 40. The front mold member 50 of the

cover section 18 may be the same as the rear member 34 of the section 17 and has end portions engaged over reduced tongues 53 of corner blocks 54. The blocks 54 may be the same as the blocks 41, except that their longitudinal tongues 53 may be shorter than the tongues 42. The blocks 54 are fitted in the forward corners of the section 18. In practice the tongues 53 of the blocks 54 are first inserted in the ends of the mold member 50 and the assembly is arranged in place on the section 18. When this is done the screws 33 for the bumpers 32 are passed through their openings in the forward flange 21 of the section 18 and are threaded into openings 55 in the blocks 54. This secures the blocks 54 and the mold member 50 to the section 18. The flanges 39 and 40 of the member 50 are engaged with or recessed in the tongue 53 to retain the member in place and the surface of the main portion 37 of the mold member lies flush with the corresponding surfaces of the blocks 54. The shoulders 56 occurring at the inner ends of the longitudinal tongues 53 cooperate with the ends of the member 50 to lock the member against endwise movement.

The end mold members 51 correspond to the above described members 35 and are engaged on the transverse tongues 53 of the blocks 54 to fit over the end flanges 21 of the section 18. The forward ends of the members 51 are straight to cooperate with the block shoulders 56 and the flanges 39 and 40 of the members engaged behind and are recessed in the tongues to lock the members against displacement. The rear ends of the members 51 may engage or may be immediately adjacent the rear rim 20 of the section 18 and bases 38 of the members 51 fit over the inner flange 21 of the section 18.

The rear mold member 52 of the section 18 corresponds to and may be identical with the forward mold member 36 of the section 17. The member 52 is arranged to have its base 38 engage the inner or upper side of the flange 21 which extends along the rear edge of the section 18 and its flange 39 bears against the rim 20 while its flange 40 bears against the under side of the section. The opposite ends of the member 52 are mitered or bevelled as at 57 to properly engage with the members 51. The ends of the member 52 are formed to fit against the members 51 to dependably retain the inner parts of the members 51. The attaching means of the hinges 29 are employed to secure the mold member 52 to the section 18. The blocks or plates 31 for anchoring the forward screws 30 of the hinges 29 are arranged against the inner or upper sides of the bases 38 of the member 52. The plates 31 may be welded or otherwise fixed to the member 52. The base 38 of the member 52 has openings 48 for passing the screws 30. When the member 52 has been arranged in place between the members 51, the screws 30 are passed through their openings in the hinges 29 and flanges 21 and the openings 48 and are threaded into the blocks 31. This dependably fixes the mold member 52 to the section 18. The mold members 50, 51 and 52 and the blocks 54 may have their exposed surfaces plated or otherwise finished.

It is believed that the features of the cover construction will be readily apparent from the foregoing detailed description. The mold members of the means 19 are securely and dependably attached to the cover sections 17 and 18 without resorting to the use of welding or attaching means that detract from the appearance of the struc-

ture or that might injure the frangible porcelain finish of the cover parts. The attaching members or screws 26, 30 and 33 already required in the cover structure are utilized to anchor or secure the mold members to the cover sections 17 and 18. These attaching parts or members are concealed or inconspicuous and are not exposed at the sides or exterior of the cover. There are no exposed or visible attaching means on the molding parts and the molding structures present smooth, continuous, unbroken surfaces. With the exception of the blocks 41 and 54 of the elements of the mold means 19 for the two cover sections 17 and 18 may be identical and, if desired, the blocks for the two mold assemblies may be the same. This promotes economy in the manufacture of the construction.

Having described only a typical preferred form and application of my invention, I do not wish to be limited or restricted to the specific details herein set forth, but wish to reserve to myself any variations or modifications that may appear to those skilled in the art or fall within the scope of the following claims.

Having described my invention, I claim:

1. A cover comprising two cover sections arranged in edge to edge relation and having edge flanges, separately formed mold members arranged at the under sides of the sections to engage with said flanges and extending along the lengths thereof, blocks engaged in the mold members, a hinge for connecting the sections for relative swinging movement and having cheeks at the under sides of the sections, and screws passed through openings in the hinge cheeks, edge flanges and mold members and threaded into the blocks to attach the hinge to the sections and to secure the mold members to their respective sections.

2. In a cover for a cooking range, a pair of cover sections arranged in edge to edge relation, depending marginal flanges on the sections, molding assemblies at the under sides of the sections engaged within the flanges, the assemblies including end mold members arranged at the opposite ends of the sections, and mold members extending along the edges of the sections which are in adjacent relation and extending between and contacting the first named mold members to hold them in place, a hinge at the adjacent edges of the sections, screw threaded parts attaching the hinge to the flanges at said adjacent edges of the sections and securing the last named mold members to their respective sections, and hinge means securing one of the sections to the range.

3. In a cover for a cooking range, a pair of cover sections arranged to have adjacent longitudinal edges in substantially parallel relation, depending rims extending along the edges of the sections at the under sides of the sections, mold assemblies engaged in the rims of the sections each including first longitudinal mold members attached to the sections and engaged in the rims which extend along the longitudinal edges of the sections opposite to said adjacent edges, end mold members engaged in the rims at the ends of the sections, second longitudinal mold members engaged in the rims which extend along said adjacent longitudinal edges and engaged between the end members to retain the same, hinges at said adjacent edges of the sections adjacent the ends of the sections, and screw threaded elements attaching the hinges to said adjacent edge parts of the sections and securing said second longitudinal members to their re-

spective sections, and hinge means securing one of the sections to the range.

4. An articulated cover comprising two generally rectangular cover sections arranged to have adjacent longitudinal edges in side by side relation, depending marginal rims on under sides of the sections, inturned flanges on the rims, mold assemblies at the under sides of the sections each comprising a first mold member engaged in the rim and flange at the edge of its section opposite to said adjacent longitudinal edges, corner blocks secured in the corners of the section at the ends of said first member and engaged in the ends of said first mold member to retain the same, end mold members engaged in the rims and flanges at the ends of the section and having their ends engaged with the blocks to be retained thereby, and second longitudinal members engaged in the rim and flange which extend along said adjacent longitudinal edge of the section and extending between and contacting the ends of the end members to retain the same in position, a hinge at said adjacent edges of the sections, and screw threaded elements arranged through openings in the flanges at the adjacent edges of the sections and the hinges to secure the hinges to the sections and to secure the second longitudinal mold members to the sections.

5. In a cover of the character described, a generally rectangular cover section of sheet material having corners where its end edges and longitudinal edges join, downturned rims on the margins of the section, inturned flanges on the rims presenting upper and lower sides, and a molding structure for the section comprising a mold member extending along one longitudinal edge of the section and engaging the upper side of its flange, corner blocks in the corners of the section at the ends of said mold member and engaged with said member to retain the same, end mold members extending along the end edges of the section to engage the upper sides of the flanges at said end edges, tongues on the blocks engaging in the end mold members to assist in retaining the end members, and a mold member extending along the other longitudinal edge of the section to engage the upper side of its flange and extending between and contacting said end mold members to assist in retaining the same.

6. An articulated cover comprising two generally rectangular cover sections arranged to have adjacent longitudinal edges in side by side relation, means hinging said edges together, depending marginal rims on the under sides the sections, inturned flanges on the rims, mold assemblies at the under sides of the sections each comprising a first longitudinal mold member engaged in the rim and flange at the edge of its respective section which is opposite said adjacent edges, corner blocks secured in the corners of the section at the ends of said first mold member and engaged in the ends of the said first mold member to retain the same, bumpers on the flange of said edge of the section, screws securing the bumpers to said flange and attaching the blocks to the section, end mold members engaged in the rims and flanges at the ends of the section and each having an end engaged with a block to be retained thereby, and a second longitudinal mold member engaged in the rim and flange at said adjacent longitudinal edge of the section and extending between and contacting the ends of the end mold members to retain the

same in position, and means for securing said second longitudinal mold members to their respective sections.

7. A cover of the character described comprising a rectangular cover section of sheet material having a down-turned rim extending along its several edges, inturned flanges on the rim, a molding assembly for the under side of the section including corner mold blocks set in the rim and flanges at the corners of the section which occur at the ends of one edge of the section, the blocks having tongues, a mold member extending along said edge of the section to engage with the rim and flange thereof and retained by tongues on the blocks, end mold members engaged with the rim and flanges at the ends of the section which join the first named edge at said corners, said end mold members having ends engaged on tongues of the blocks to be retained thereby, a mold member at the edge of the section opposite said first named edge and engaged with the rim and flange thereof and extending between and contacting the other ends of the end mold members to retain the same, means securing the last named mold member to the flange at the last named edge of the section, and means securing the blocks to the cover section.

8. A cover of the character described com-

prising a rectangular cover section of sheet material having a down-turned rim extending along its several edges, inturned flanges on the rim, a molding assembly for the under side of the section including corner mold blocks set in the rim and flanges at the corners of the section which occur at the ends of one edge of the section, the blocks having tongues, a mold member extending along said edge of the section to engage with the rim and flange thereof and retained by tongues on the blocks, end mold members engaged with the rim and flanges at the edges of the section which joint the first named edge at said corners, said end mold members having ends engaged on tongues of the blocks to be retained thereby, a mold member at the edge of the section opposite said first named edge and engaged with the rim and flange thereof and extending between and contacting the other ends of the end mold members to retain the same, means securing the last named mold member to the flange at the last named edge of the section, hinges at the first named edge of the section for mounting the section on a support, and screws attaching the hinges to the section and securing the corner blocks to the section.

LOUIS J. SMALLEN.
